(57) **CLAIM**

The ornamental design for a textile machine as shown and described.

DESCRIPTION

The patent or application file contains at least one drawing executed in color. Copies of this patent or patent application publication with color drawing(s) will be provided by the Office upon request and payment of the necessary fee.

1. Textile machine

1.1 : Front Perspective

1.2 : Rear Perspective

1.3 : Front

1.4 : Back

1.5 : Right

1.6 : Left

In reproductions 1.1 to 1.6, the areas colored in yellow show portions of the article that form no part of the claimed design.

1 Claim, 6 Drawing Sheets
(6 of 6 Drawing Sheet(s) Filed in Color)
